DIRECTIVE HIGH-FREQUENCY ANTENNA

Stanley L. Breen, Cambridge, Lan Jen Chu, Brookline, and Chia-Shan Pao, Cambridge, Mass., assignors, by mesne assignments, to the United States of America as represented by the Secretary of War

Application January 24, 1945, Serial No. 574,368

2 Claims. (Cl. 250—33.65)

1

The present invention relates to an antenna for use in a high frequency communication system and is particularly directed to an antenna adapted to discontinuously scan portions of space.

Accordingly, the principal object of this invention is to provide an antenna which is adapted to radiate electromagnetic waves of high frequency energy in a distribution pattern which shifts in discrete steps through a plurality of regions in space rather than scanning continuously.

It is also an object of the invention to obtain a discontinuous scan by providing a group of spaced radiating elements and means for radiating energy from one or more of the elements in a predetermined arrangement or sequence to provide a variety of scanning patterns.

It is another object of the invention to provide an antenna adapted to discontinuously search a portion of space and which is economical to construct and easy to operate.

Other objects and advantages of this invention will become apparent as the description proceeds, reference being made to the accompanying drawings in which:

Fig. 1 is a side elevation view, partly broken away, of one embodiment of an antenna according to the invention; with a circular wave guide, and with a parabolic reflector shown diagrammatically;

Fig. 2 is a front elevation view of the antenna according to the invention looking to the right from the reflector of Fig. 1; and

Fig. 3 is a sectional view, partly broken away, of said reflector taken on the line 3—3 of Fig. 2.

Referring to the drawings, a parabolic reflector is diagrammatically indicated at 10 in Fig. 1. Mounted in front of reflector 10 is a circular hollow wave guide 11, adapted to be excited by energy from a source (not shown), preferably in the TE_{1,1} mode and polarized as indicated in Fig. 3, the arrows E representing the direction of the electric lines of force. Wave guide 11 is generally disposed so that a plane tangential to its surface and perpendicular to the axis of reflector 10 passes through the focal point F of reflector 10.

A plurality of slots are disposed in the wave guide 11 and are symmetrically spaced about and near the focal point F. As shown more clearly in Fig. 2, guide 11 is provided preferably with four slots, 12, 13, 14 and 15, having their longitudinal axes parallel with the longitudinal axis of guide 11. The length of each of the slots is generally a half wavelength of the operating wavelength of 55

2

the exciting energy so that the slots are properly matched to space. Energy from guide 11 is adapted to be radiated from the respective slots toward the reflector 10 from which it is reflected into space in a directional manner.

Mounted coaxially relative to guide 11 is a cylindrical sleeve or collar member 16. Sleeve 16 surrounds the guide 11 in closely fitting relation thereto over a substantial portion of the length 10 of the guide 11. Sleeve member 16 is rotatably mounted relative to guide 11 in any suitable manner such as by a ball bearing raceway generally indicated at 17 in the broken away portion of Fig. 1. Any suitable means may be used 15 for rotating sleeve 16 about guide 11; for example, a ring gear 18 may be mounted on the lower peripheral surface of sleeve 16 mating with gear 19 and driven through shaft 20 by motor 21.

Sleeve 16 is provided with a group of apertures 20 or slots so disposed that only one of the apertures at a time will match or register with one of the slots in guide 11 and the remaining slots in guide 11 will be covered by the solid wall of cylindrical sleeve 16. For example, when guide 11 is provided with four slots, 12, 13, 14 and 15, as referred to above, sleeve 16 is preferably provided with four apertures 22, 23, 24 and 25. These apertures may be of any suitable dimensions, but preferably of substantially the same vertical dimensions 25 as the length of the slots in guide 11.

As shown more clearly in Figs. 2 and 3, apertures 22, 23, 24 and 25 are spaced symmetrically in sleeve 16 with the width of the apertures, in the illustrated example, being equal to about a 30 40° arc of the peripheral surface of cylindrical sleeve 16. Apertures 22 and 24 are preferably disposed diametrically opposite to apertures 23 and 25 respectively, with adjacent apertures being disposed radially substantially 90° apart.

40 As shown, slots 12 and 13 and apertures 22 and 23 are located on one side of the axis of reflector 10, and slots 14 and 15 and apertures 24 and 25 are located on the opposite side of the reflector axis. Aperture 23 is shown corresponding with, 45 or in registry with, slot 13; thus permitting radiation of energy from slot 13 toward reflector 10, the remaining slots being closed and effectively short-circuited by the solid wall of sleeve 16.

As sleeve 16 is rotated, for example in a clockwise direction (Fig. 3), aperture 23 moves out of 50 registry with slot 13 and into registry with slot 12, slot 13 thereby being closed by the wall of sleeve 16. Continued rotation brings aperture 25 into registry with slot 15 and then slot 14, and aperture 22 into registry with slots 13 and 12

consecutively. Further rotation of sleeve 16 begins another cycle.

As mentioned, radiating slots 12, 13, 14 and 15 each are displaced from the focal point F of reflector 10. Therefore radiations emanating from each of the slots (as permitted by rotating sleeve 16) will be directed by reflector 10 along a path of radiation which makes an angle with the axis of the reflector. The size of the angle, of course, is proportional to the amount the radiating slot is displaced from the focal point F. In the illustrated antenna having four radiating slots as shown, there are thus four separate paths of radiation adapted to be independently illuminated according to a predetermined sequence. Preferably the radiation pattern of each individual beam overlaps the radiation pattern of one or more of the other beams. Such a system provides a scanning action of the portion of space included within the composite pattern of radiation.

By suitable arrangement of the mentioned apertures and slots any desired sequence of radiation from the slots may be provided. Thus any desired scanning pattern may be obtained by the present invention merely by suitably arranging the slots in the wave guide 11 and the apertures in the sleeve 16.

Thus it will be apparent that as radiation occurs first from one slot and then from another according to a predetermined arrangement, energy is radiated in a distribution pattern which shifts from section to section in space in a discontinuous scan.

While an embodiment of the invention is illustrated herein, it will be understood that many different arrangements of any number of radiating elements, i. e. slots, wave guides, horns, etc., are possible with the present invention. The elements may be fed in series or parallel, as desired. Similarly any predetermined sequences of illumination of the elements may be used.

We claim:

1. An antenna for use in a high frequency communication system comprising, in combination, a parabolic reflector, a hollow circular wave guide adapted to transmit high frequency electromagnetic energy mounted in front of said reflector so that a plane tangential to its surface and perpendicular to the axis of said reflector passes substantially through the focal point thereof, a cylindrical sleeve rotatably mounted in closely fitting coaxial relation around said wave guide, said wave guide having a plurality of slots spaced symmetrically with reference to said focal point, the longitudinal axes of said slots being parallel with

the longitudinal axis of said wave guide, the length of each said slot being substantially half the operating wavelength of the electromagnetic oscillations, said sleeve having a plurality of spaced apertures, and means for rotating said sleeve whereby said apertures are adapted to register successively with said slots in a predetermined sequence for permitting energy to be radiated from said slots one at a time, the remaining slots being closed and effectively short-circuited by said sleeve, for thereby enabling said antenna to discontinuously scan in a distribution pattern which shifts in discrete steps through a plurality of regions in space.

2. An antenna as claimed in claim 1 in which the wave guide is provided with four slots, said slots being spaced symmetrically with reference to the focal point of the reflector, two of said slots being parallel to each other on one side of the axis of said reflector, the other two of said slots being parallel to each other on the opposite side of the axis of said reflector, and in which the sleeve is provided with four apertures, the length of each aperture being substantially equal to the length of said slots and the width of each aperture being substantially wider than the width of said slots, two of said apertures being located diametrically opposite each other and adapted to be rotated into registration with said first-mentioned two slots, the other two of said apertures being located diametrically opposite each other and adapted to be rotated into registration with said second two slots.
